DART GUN

Moses S. Shirn, Williamsport, Pa.

Application February 18, 1937, Serial No. 126,464

4 Claims. (Cl. 273—107.5)

This invention relates to the class of toy guns and pertains particularly to a gun designed for the shooting of darts or similar devices suitable for use in connection with games where targets are set up to be shot at.

The primary object of the present invention is to provide a new and novel gun constructed along the general principle of a cross-bow, wherein novel means is devised for projecting a dart or similar device forwardly through a barrel or other suitable guide means.

Another object of the invention is to provide a toy gun of the character stated in which novel means is provided for loading the gun, or in other words, for placing a dart in position ready for shooting.

A still further object of the invention is to provide a gun of the cross-bow type in which novel means is provided for holding the bow string and for releasing the same when the gun is to be fired.

The invention will be best understood from a consideration of the following detailed description taken in connection with the accompanying drawings forming part of this specification, with the understanding, however, that the invention is not confined to any strict conformity with the showing of the drawings but may be changed or modified so long as such changes or modifications mark no material departure from the salient features of the invention as expressed in the appended claims.

In the drawings:
Figure 1 is a view in side elevation of a gun constructed in accordance with the present invention.

Fig. 2 is a view in top plan.
Fig. 3 is a view upon a slightly enlarged scale

Fig. 4 is a sectional view taken on the line 4—4 of Fig. 3.

Fig. 5 is a sectional view taken on the line 5—5 of Fig. 3.

Fig. 6 is a sectional view on the line 6—6 of Fig. 2.

45 Fig. 7 is a view in side elevation of a portion of the dart conveyor by which a dart is moved into

Referring now more particularly to the drawings, the numeral 1 generally designates the stock.

ings, the numeral 1 generally designates the stock of the gun which has its forward portion cut out in the usual manner as indicated at 2 to form a comfortable hand grip, and which at its forward end is constructed in the usual manner of rifle stocks, to provide the fore-stock portion 3 upon which the rear of the gun barrel is mounted.

In the hand-grip area of the stock there is formed vertically through the stock the trigger slot 4, in which is mounted transversely of the stock and the slotted area the trigger pin 5 upon which is mounted the trigger 6. The lower end of the trigger projects in the usual manner below the underside of the stock and is shielded by the trigger guard 7, and the upper end of the trigger above the pivot 5 extends to within a short distance of the top of the opening 4 and carries upon its upper end the forwardly extending loop 8 through which passes the transverse bar 9. This bar 9 has its ends extended through slots 10 which are formed in the side walls of the stock and open into the trigger slot 4 and which are slightly arcuate, as shown, so that when the projecting end of the trigger 6 is drawn back, the loop 8 can swing the bar 9 downwardly to retract the projecting upper ends of latch fingers 11. The latch fingers 11 form the upper terminals of rocking bars 12, each of which is pivotally attached as at 13 to the outer side of the gun stock and extends upwardly and forwardly across the adjacent end of the bar 9 so that the rear bar can be attached to the rocking bar and thus when the bar 9 is swung downwardly by oscillation of the trigger the upwardly projected finger portions 11 of the rocking bars 12 will be swung forwardly and downwardly. These fingers 11 normally project above the top of the gun stock for the purpose hereinafter described. The rocking bars are normally held with the fingers 11 projected upwardly by the spring 13 which is housed in the slot 4 and has one end attached to the stock and the other end attached to the trigger so as to normally pull the lower end of the same forwardly.

Mounted upon the top of the fore-stock in what would be, in a standard type rifle, the breech area, is a relatively long plate 14 which has a flat top surface and which has a portion of each longitudinal edge turned inwardly to form a flange 15 which is in spaced relation with the body of the plate and thus forms a guide groove 16, as illustrated in Fig. 4. The rear end of this elongated slide plate over which a dart is moved, as will be hereinafter described, is cut out, as indicated at 17, and this cut-out area is closed by the removable plate 18 which at its rear end is secured to the gun stock, as indicated at 19. This plate covers the top of the trigger slot 4, and it has formed therethrough just to the rear of the slot 4, the cord opening 20 which overlies the downwardly and rearwardly extending passage 21 which passes through this stock to a groove 22 formed upon the underside of the hand grip area 55

of the stock. This groove 22 extends rearwardly to the chamber 23, and this chamber has a shaft 24 passing transversely therethrough. One end of this shaft is rotatably mounted in the stock and the other end passes out through the side of the stock and terminates in the crank 25.

The rocking bars 12 and the slots 10 are covered by the face plates 26 which are secured to the sides of the stock, and these plates may be provided with suitable apertures 27 to form a means for oiling the trigger mechanism without necessitating the removal of the plates. The dart guide plate extends forwardly from the trigger area through only a portion of the length of the fore-stock 3, where it abuts the rear end of the barrel 28. The barrel may extend forwardly any desired distance beyond the fore-stock so that the toy will simulate a rifle. The forward end of the barrel is provided with a front sight 29, while at the rear end of the barrel a V sight 30 is mounted, and one edge of the plate of which this V sight is formed, is integral with the forward end edge of an elongated guard plate 31 which extends rearwardly from the sight 30 to the rear part of the breech and is provided with the downwardly extending ears 32 which are attached to the side of the stock. The lower edge of this guard plate 31 is spaced slightly from the adjacent portion of the stock and from the plate 14, for the purpose hereinafter pointed out.

Secured across the front edge of the fore-stock is a short resilient plate 33, and secured over this plate is the relatively long bow spring 34. The attachment of the spring with the fore-stock is midway between the ends of the spring, and these ends have a bow string or wire 35 connected therewith, which passes through between the guard plate 31 and the plate 14 and across the top of the latter plate.

40. Mounted for movement longitudinally of the plate 14 is a propeller which comprises a socket-like element 36 which is attached to a rider plate 37 which rests upon the dart guide plate 14 and has its opposite side edges engaged in the inwardly facing guide grooves 16. This propeller has a suitable transverse passage formed in the rearwardly extending eye 38 for the bow string 35 to pass through, and also attached to the eye 38 is one end of a draw string 39 which passes rearwardly through the opening 20 and to the crank shaft 24 by way of the passage 21 and slot 22. It will thus be apparent that when the shaft 24 to which the rear end of the string 39 is attached, is rotated to wind up the string, the propeller will be drawn back and also the central part of the bow string 35 to flex the bow, as illustrated in Fig. 2, and when the propeller is at the limit of its rearward movement, the parts of the bow string at each side thereof will lie just behind the latch fingers 11, and when the gun is prepared for firing it is necessary to draw back upon the trigger 6 so as to retract the fingers 11 and allow the string to pass over them and then the trigger is released to allow the fingers to 65 rise in front of the bow string where it will be held by both of the fingers and the gun will be cocked and ready for firing.

As will be seen from Fig. 2, the bow string held fingers project upwardly from between the facing plates 26 and the side edges of the dart guide plate 14, and one of these fingers lies between the guard plate 31 and the plate 14.

Upon the side of the plate 14 opposite from the guard plate 31 there is mounted a pivot pin 40 which extends longitudinally of the side edge of

the plate 14 and carries between the hinge ears 41 a dart carrying trough 42. This trough is secured to the pin 40 so that when the latter is rocked in a counter-clockwise direction the trough will swing upwardly and inwardly toward the center of the plate 14 and thus a dart previously placed in the trough will be rolled over into the area between the guide flanges 15 and if the gun is held in upright or upwardly inclined position when this operation is carried out, the dart will slip back so that its rear end will enter the propeller unit 36.

In order to facilitate this oscillation of the dart trough, there is mounted transversely in the fore-stock the rock shaft 43 which has a lifting crank 44 upon that end which lies beneath the trough 42, while the other end is provided with a suitable offset crank 45 to which one end of a contractile spring 46 is attached, while the other end of this spring is attached to the gun stock and thus the spring tends to oscillate the shaft 43 so as to move the lifting crank 44 away from the trough. The shaft 43 adjacent the crank 45 is suitably formed, as indicated at 47, to facilitate the oscillation of the shaft by the user of the gun. Thus it will be apparent that in the use of the gun when the bow string has been drawn back by rotating the crank shaft 24 in the manner described and the trigger controlled fingers have been placed in engagement with the bow string to hold the bow flexed, the dart previously placed in the trough 42 can be conveniently thrown over into shooting position by the oscillation of the shaft 43. After the end of the dart has engaged in the propeller 36 in the manner previously described, release of the bow string by actuation of the trigger will project the propeller forward and also the dart, and as the rider plate 37 comes into violent contact with and is stopped by the rear edge of the barrel 28, the dart will be projected forward through and out of the barrel.

In order that additional darts may be kept conveniently at hand, the stock may be provided with a chamber 48 which can be kept closed by the plate 44 pivotally attached to the stock and secured in any suitable manner. While an elongated dart chamber has been illustrated it will be apparent that a chamber of any other configuration may be made use of without departing from the spirit of the invention.

It should be additionally pointed out that in the operation of the gun, after the bow wire 35 has been drawn back by means of the crank 25 and cord 39, before the gun can be fired the cord 39 is drawn forwardly through the opening 20 so as to unwind enough of it from the shaft 24 to allow the dart projector to move forward freely.

From the foregoing it will be readily apparent that the gun herein described is of novel character and may be used in the playing of games where a target is shot at.

What is claimed, is:

1. A dart gun comprising an elongated body including a stock, a breech and fore-stock, an elongated guide plate mounted upon the fore-stock adjacent the breech portion thereof, a barrel extending forwardly from the forward end of said plate, a rider plate slidably mounted upon the guide plate, a dart propeller carried by the rider plate, spring means connected with said propeller and adapted to be placed under tension when the propeller is moved into the breech area of said stock, propeller holding means for maintaining the propeller in position with said

- 5 resilient means under tension and releasable by said trigger, a dart carrier pivotally mounted at one side of said guide plate for oscillation on an axis extending longitudinally of the guide plate, and means for oscillating said carrier on said axis to transfer a dart therefrom onto the guide plate immediately in front of said propeller.
- 10 2. A dart shooting gun, comprising an elongated body consisting of stock, breech portion, and fore-stock, an elongated plate secured to the top of the body and having a rear end overlying the breech portion, flanges extending longitudinally of and spaced from the plate forming guide grooves extending through the length of the guide plate, a barrel extending forwardly from the fore-stock and over the forward end of said guide plate, a trigger pivotally mounted in said breech portion, a pair of finger members rockably mounted upon the breech portion of the body and having the body therebetween, the finger members normally projecting above said guide grooves, a flat rider plate mounted upon said guide plate and having its edges engaged in said grooves, a dart propeller carried by the rider plate, a resilient bow secured transversely of the fore stock, and a bow string connecting the ends of the bow and extending across the guide plate behind and engaging said propeller, said fingers operating to engage the bow string upon either side of the propeller when the bow string is drawn back to retain said propeller against movement.
- 15 3. A dart gun comprising a stock, a breech portion and a fore stock, said breech portion having a chamber opening through the top and through the under side thereof and said chamber having the side walls thereof provided with arcuate slots, a propeller mounted upon said fore stock for longitudinal movement, means parallel-
- 5 ing the fore stock for guiding the propeller, a bow secured across the forward end of the fore stock, a bow string connecting the ends of the bow and extending across the supporting surface for said propeller and engaging behind the latter, a trigger pivotally mounted within said chamber, a bar extending transversely through the chamber and having its ends passing outwardly through said arcuate slots, and bow retaining fingers pivotally mounted upon the outer sides of the breech and joined by said bar and having their ends projecting upwardly for engagement by the bow string when the latter is drawn back to tension the bow, and connecting means between the trigger and the bar for oscillating the fingers 10 downwardly for the release of the bow string.
- 10 4. In a dart gun, a stock, a breech and fore stock integral therewith, a guide plate extending longitudinally of the top surface of the fore stock, a dart propeller slidably mounted upon said guide plate, a bow secured transversely of the forward end of the forestock, a string connecting the ends of said bow and extending across the guide plate and behind and in engagement with said propeller, trigger release means carried 20 by the breech and adapted to engage the bow string when the propeller is drawn back to maintain the propeller in said position, a vertically disposed plate extending longitudinally of the breech and a portion of the fore stock and at one 25 side of the guide plate, a dart carrying receptacle mounted upon an axis extending longitudinally of the guide plate and at the opposite side of the same from the vertically disposed plate, and means for oscillating said receptacle upwardly and 30 inwardly toward the guide plate to deposit a dart from the receptacle onto the guide plate.
- 35

MOSES S. SHIRN.
